Inventor:

P. Gerst.

UNITED STATES PATENT OFFICE

PAUL GERST, OF ALTSTETTEN-ZURICH, SWITZERLAND

AUTOMATIC FIRE ALARM

Application filed February 9, 1928, Serial No. 253,133, and in Switzerland November 17, 1927.

This invention relates to an electric device for use principally as an automatic fire alarm, and the invention consists in the provision of an insulating block across which a pair of wires, forming part of an alarm circuit, is stretched and normally separated by distanced studs connected to the block, one of said studs being adapted to fuse readily so as to allow the wires, which are tensioned transversely, to make contact with the other stud for closing the alarm circuit if the temperature in the room should rise excessively.

Fig. 1 of the accompanying drawings is a diagrammatic view of the device as applied to a wall or the like,

Fig. 2, a sectional view of the insulating block and its cover, and

Fig. 3, a view of a wire support used in conjunction with the insulating block.

The alarm circuit includes a pair of wires *b* and *c* which are stretched along a wall or a ceiling. One of the supports for the wires consists of a block *e* of insulating material to which two studs *f* and *g* are secured at a distance apart. The stud *f*, which is preferably elongated in the direction of the stud *g*, as shown, is made of brass, whereas the smaller stud *g* is made of some material such as wood-metal or the like, adapted to fuse readily, say

at about 60° C. The block is provided with a cover *h* which is formed with apertures *m* and *n* allowing the air to circulate freely across the stud *g* so as to fuse it if the temperature in the room should rise sufficiently.

The wires *b* and *c* are led through the box thus formed, the wire portions inside the box being bared and placed on the studs *f* and *g* so as to be normally kept apart by the latter. Tension is applied to the wires so that if the stud *g* should fuse, both wires will be applied to the stud *f* and connected electrically through the latter for closing the alarm circuit.

The wire portions outside the box are insulated with some readily combustible material. Preferably they are first covered with a layer of wood metal and then with cotton which in its turn is covered with artificial silk. These insulated wire portions, which are twisted together, are supported by studs

or rollers *a* to which coil springs formed with arms *d* are applied. The arms *d* are engaged in the twin wires so as to apply tension to the latter. If the insulation should burn through, the wires will be caused by the tension to contact with each other and close the alarm circuit. Thus the alarm will be operated whether the wires be exposed direct to the flame or merely to the heat.

I claim:

1. An automatic fire alarm comprising an insulating block, a pair of wires stretched across said block and tensioned transversely so as to have a tendency to meet, and a pair of distanced studs on the block whereby said wires are normally separated, one of said studs being adapted to fuse at excessive room temperature so as to allow the wires to be electrically connected through the other stud.

2. A structure as claimed in claim 1 wherein the wire portions outside the block bear against each other and are relatively insulated with readily combustible material, and including means for tensioning the wires consisting of studs which hold the insulated wire portions, and spring arms arranged on said latter studs and engaging the adjacent wire portions.

PAUL GERST.
